Attorney.

UNITED STATES PATENT OFFICE.

ALBERT H. SIEVERT, OF LOS ANGELES, CALIFORNIA, ASSIGNOR OF ONE-HALF TO CHARLES W. SIEVERT, OF LOS ANGELES, CALIFORNIA.

HYDROCARBON-BURNER.

No. 918,781.

Specification of Letters Patent. Patented April 20, 1909.

Application filed August 25, 1908. Serial No. 450,210.

To all whom it may concern:

Be it known that I, ALBERT H. SIEVERT, a citizen of the United States, residing in Los Angeles, county of Los Angeles, and State of California, have invented new and useful Improvements in Hydrocarbon-Burners, of which the following is a specification.

My invention relates to the class of hydrocarbon burners in which crude oil, or other liquid-fuel is burned by the aid of some 10 expansible-fluid, such as steam, or compressed air, and the object thereof is to produce a burner in which the expansible-fluid can be delivered into the combustion chamber 15 below the liquid-fuel in a broad thin stream which can be readily regulated as to the thickness of the stream by the operator. I accomplish this object by the burner described herein and illustrated in the accompanying drawing, in which,

Figure 1 is a central longitudinal section of the burner tip and showing the front wall of the combustion chamber and a portion of the supply pipes. Fig. 2 is a plan of the 25 parts shown in Fig. 1, a portion of the burner tip being in section. Fig. 3 is a front elevation of the burner tip. Fig. 4 is a rear elevation of the burner tip.

In the drawings 5 is the front wall of the 30 combustion chamber and is provided with an opening 6 therethrough which is covered by a cap plate 7 if desired, said cap plate having holes through which the projecting exterior part of the burner and the supply 35 pipes extend. The burner tip is composed of a body piece 8 which is preferably cylindrical in shape with the lower portion thereof of less diameter than the upper portion. In the upper portion is a transverse liquid-fuel 40 channel 9 which extends through the head. The rear end of this channel is enlarged and interiorly threaded for the reception of the fuel supply pipe 10 which screws into the head. This supply pipe is provided with a 45 cock 11 to regulate the supply of fuel to the burner, and runs to a supply of liquid not shown. Extending longitudinally and centrally and then transversely in the lower portion of the body piece is the expansible- 50 fluid channel 12 best shown in Fig. 1. This channel opens in a port at the front of the burner just below the liquid-fuel channel port and a little back of the same. Around the outlet, the body piece is cut away to form a 55 recess 13 best shown in Fig. 3. On the lower reduced portion of the body piece is a sleeve

14 which is provided with an upwardly projecting lip 15, which lip is adapted to fit into the recess 13 to close the same when the upper portion of the sleeve is in contact with the 60 enlarged portion of the body. The outlet of channel 12 is square and preferably of the same width as lip 15 so that the expansible-fluid will issue from said channel in a thin 65 broad stream when the sleeve is moved downwardly on the body.

In the back portion of the sleeve is an elongated opening 16 in which is received a cam 17 which is mounted eccentrically on rod 18 to which it is rigidly secured by a pin 19 70 which passes through the cam and rod to secure the parts together. The inner end of rod 18 passes into a recess 20 in the body piece and is revoluble therein, so that as rod 18 is rotated the sleeve is moved up or down 75 on the body to open or close port 21 which is formed between lip 15 and the upper part of the body piece. A two part strap 22 having its parts secured together by screws 23 and having an opening 24 through which stem 18 80 passes, holds the cam from separating from the sleeve. A plate could be fastened to the sleeve to hold the cam in place. A supply pipe 25 provided with a regulating cock 26 passes through the furnace wall and projects 85 in front of the burner tip and then rearwardly and connects to channel 12 in the burner tip to supply expansible-fluid from a source of supply not shown. If desired the body piece of the top could be of uniform diameter and the expansible - fluid channel 90 open at the surface thereof and the sleeve could be placed on the outside of the lower portion of the body piece and be operated by the cam to open and close the port of channel 95 12. That portion of the expansible-fluid 100 pipe which projects in front of the burner tip may be termed a superheater and if desired the same could be omitted, but I prefer its use because it better prepares the expansible-fluid for combustion.

Having described my invention what I claim is;

1. A hydro-carbon burner comprising a cylindrical body piece the lower portion of 105 which is of less diameter than the upper portion having a square shaped recess in the front portion of the lower part of the enlarged upper portion of the body piece and having an expansible-fluid channel terminating in a square port in said recess and a 110 liquid-fuel channel terminating in a port

above said recess; a sleeve slidably mounted upon the lower portion of said body piece, said sleeve having a lip projecting upwardly and adapted to fit into the recess of the upper portion of the body piece; and means to move said sleeve longitudinally upon said body piece.

2. A hydro-carbon burner comprising a cylindrical body piece and having the lower portion of less diameter than the upper portion and provided with a liquid-fuel channel and an expansible-fuel channel and a recess in the top portion, said expansible-fluid channel terminating in a square port in said recess; a sleeve provided with a lip and slidably mounted on the lower portion of said

body piece, said sleeve having an elongated opening in the back portion thereof; a rod revolvably mounted in the lower parts of said body piece; a cam eccentrically mounted on said rod, said cam being adapted to work in the opening in said sleeve; and means to prevent said cam from accidentally separating from said sleeve.

In witness that I claim the foregoing I 25 have hereunto subscribed my name this 19th day of August, 1908.

ALBERT H. SIEVERT.
